CHEMOTHERAPEUTIC COMPOSITIONS INCLUDING ESTERS OF INDOLYL-3-ACETIC ACID

David Norman, Redondo Beach, and Robert D. Schultz, Whittier, Calif., assignors to North American Aviation, Inc.
No Drawing. Filed Mar. 20, 1964, Ser. No. 353,617
17 Claims. (Cl. 167—78)

In the practice of this invention according to a preferred embodiment there is provided a treatment which effects a carcinolytic action comprising exposing Ehrlich ascites tumor cells to the action of an ester of an auxin. Esters of auxins that are preferred include alkyl esters of indolyl-3-acetic acid (indoleacetic acid) and naphthyl-1-acetic acid wherein the alkyl group has from one to twelve carbon atoms. It has been found that aqueous pharmaceutical preparations of such esters are effective in killing Ehrlich ascites tumor cells in tumor infected mice.

It appears that concentrations of greater than 2×10^{-2} molar indolyl-3-acetic acid in a tumor is toxic to the tumor cells in vitro. It is postulated that lower concentrations of indolyl-3-acetic acid are normally present in cells as a natural intermediate in the metabolism of the cells. Treatment employing indolyl-3-acetic acid or naphthyl-1-acetic acid as a carcinolytic agent is not effective because of the relative toxicity of these materials in normal tissue, and a somewhat protective effect which has been found when tumor cells are exposed to indolyl-3-acetic acid or naphthyl-1-acetic acid.

Modification of the indolyl-3-acetic acid to the ethyl ester thereof showed a pronounced carcinolytic action in vitro, however, the tumor cells rapidly degrade the ethyl ester, thereby reducing the efficacy of this material as a chemotherapeutic agent. Further modification of the chemical structure of the auxin in order to reduce the rate of degradation and the toxicity of the agents produces agents having a carcinolytic activity with minimized effect on normal tissue.

One group of auxin esters has the structural formula

where R is an alkyl group having from one to twelve carbon atoms substituted for the hydrogen of indolyl-3-acetic acid. Higher numbers of carbon atoms may yield chains sufficiently long to effect a steric hindrance to effective action, and show increased toxicity in aqueous suspensions. Significantly increased carcinolytic activity has been found in the group of esters of indolyl-3-acetic acid wherein R is selected from the group consisting of normal butyl, tertiary butyl, normal pentyl, normal heptyl, and normal undecyl.

It has also been found that alkyl esters of naphthyl-1-acetic acid have a significant carcinolytic effect. These compounds have the structural formula

2

where R is an alkyl group having from one to twelve carbon atoms substituted for the hydrogen of the naphthyl-1-acetic acid. Higher numbers of carbon atoms yield esters that show increased toxicity in aqueous suspensions without increased efficacy. Significantly increased carcinolytic activity has been found in the group of esters of naphthyl-1-acetic acid when R is selected from the group consisting of methyl, ethyl, normal propyl, and normal pentyl.

It has been found that the auxin esters possess a tolerated dosage level that is dependent on the alkyl group substituted on the auxin. The maximum dosage that is safely tolerated without toxic side effects is indicated by reference to the LD₅₀ set forth hereinafter. The LD₅₀ of a material is the dosage level having lethal toxicity for about 50% of the test animals to which the material is administered.

Generally, however, it has been found preferable to administer from about 200 to about 600 milligrams of auxin ester per kilogram of body weight of mice. Lower concentrations may not be completely effective in all cases and higher doses are seldom required to kill all free malignant tumor cells.

Administration is preferably with the aid of a pharmaceutical carrier. The auxin esters are soluble in many oily materials commonly employed as pharmaceutical carriers such as, for example, mineral oil, lard, cottonseed oil, peanut oil, sesame oil or the like, and are insoluble in water or in aqueous vehicles such as saline, glucose, gelatine or the like. In vitro tests of the auxin esters suspended in Krebs-Ringer glucose solution established the carcinolytic activity of the auxin esters and in vivo tests were conducted for candidate materials having tolerable LD₅₀ values. However, it was found that administration of the auxin esters in solution in the tested oily pharmaceutical carriers gave no measurable effect on tumor infected mice.

Unexpectedly it was found that similar concentrations in aqueous suspension demonstrated a beneficial effect. The auxin ester is suspended in the aqueous medium by a suspending, emulsifying, or surface active agent. Preferably a combination of surface active agent and emulsifier are employed in saline to prepare a suspension of the auxin ester. Typical materials employed in the preparation of aqueous suspensions include gum arabic, methyl cellulose, acetylated monoglyceride (available commercially as Myvacet from Distillation Products Industry, a division of Eastman Kodak Company), monomethyl glyceride, dimethyl glyceride or a moderately high molecular weight polysorbitan (commercially available under the trade names Tween or Span from Atlas Powder Company, Wilmington, Delaware). Other materials employed in the preparation of chemotherapeutic compositions containing an auxin ester may include glutathione, 1,2 propanediol, glycerol and glucose. Additionally the pH of

55 the composition is adjusted by use of an aqueous solution such as tris(hydroxymethyl) aminomethane (tris buffer).

It is postulated that the oily pharmaceutical carriers which dissolve the auxin esters and permit high dosages also serve as a preferential solvent so that little of the drug can enter the cell metabolic system before degradation. Therefore such carriers are ineffective and tests employing such vehicles give an indication that the candidate drugs are ineffective. It is found, however, that the auxin esters are effective when appropriately administered, that is, in an aqueous vehicle. A suspending agent or combination of suspending agents is employed to disperse the insoluble auxin ester and permit interaction with tumor cells. Likewise it has been found valuable to provide a water soluble material in which the auxin ester is somewhat soluble in the pharmaceutical carrier. Thus,

for example, a material such as 1,2 propanediol is employed in the vehicle to provide a small solubility of the auxin ester in the vehicle. This probably permits more rapid entering of the auxin ester into the metabolic chain of the tumor cells.

It is preferred that the auxin ester be suspended in the aqueous medium with a concentration in the range of from two to 50 mg./ml. Lower concentrations than two mg./ml. require the administration of needless quantities of liquid which must be assimilated by the mice. Higher concentrations than 50 mg./ml. are difficult to maintain in suspension and are preferably avoided.

It has been found in tests made *in vivo* that the alkyl esters of auxins cause a reversion of the Ehrlich tumor to a less virulent form. The Ehrlich carcinoma is a strain originally identified as a solid tumor. In propagating this tumor a liquid ascites tumor was isolated by Ehrlich and the resultant Ehrlich ascites carcinoma is a commonly used transplantable liquid tumor. The liquid ascites tumor is considerably more virulent than the solid form of the Ehrlich carcinoma.

A conventional technique of propagating the liquid Ehrlich ascites carcinoma for laboratory study was employed to maintain the strain. Male Webster white Swiss mice infected with the tumor were sacrificed and the ascitic fluid was collected. This fluid containing a high concentration of malignant cells was diluted with physiological saline and an aliquot was intraperitoneally injected into healthy mice to cause a malignant growth therein. Some of these mice having transplanted tumors were later sacrificed to provide ascitic fluid having malignant tumor cells to further propagate the tumor in additional animals. Some animals having transplanted liquid tumors were employed in examples set forth hereinafter.

In the course of tests, some of the animals infected with the liquid Ehrlich ascites carcinoma received treatment with an auxin ester. It was found that treatment with the tertiary butyl ester of indolyl-3-acetic acid or with the normal pentyl ester of indolyl-3-acetic acid caused a reversion of the liquid Ehrlich ascites carcinoma to a semi-solid Ehrlich ascites carcinoma which formed in the peritoneal cavity on the surfaces therein. The semi-solid tumor was collected from sacrificed mice, macerated and suspended in physiological saline. A portion of this suspension was intraperitoneally injected in healthy mice to transplant the resultant tumor. In each instance, it was found that the mice having the transplanted semi-solid tumor cells developed a semi-solid tumor having the same apparent characteristics as the parent semi-solid tumor. The semi-solid tumor produced by reversion after treatment with the normal pentyl ester of indolyl-3-acetic acid was propagated in many animals to maintain the strain. Some of the animals having transplanted semi-solid Ehrlich ascites carcinoma were employed in examples set forth hereinafter.

The treatment which caused the reversion of the liquid tumor to the semi-solid tumor comprised a single one milliliter intraperitoneal injection of drug one day after transplanting the liquid tumor. One drug comprised 25 mg./ml. normal pentyl ester of indolyl-3-acetic acid, 50 mg./ml. glucose, 18 mg./ml. 1,2 propanediol, 3 mg./ml. Myvacet, and 5 mg./ml. Tween 20 diluted to volume with 0.5% saline and buffered to 7.2 to 7.4 with tris buffer. Another drug comprised 10 mg./ml. of tertiary butyl ester of indolyl-3-acetic acid and the same vehicle as recited above. In each instance a semi-solid tumor was found upon sacrifice of the animals. The tumor resulting from the normal pentyl ester treatment was employed in examples set forth hereinafter.

The semi-solid strain is a reversion of the liquid Ehrlich ascites carcinoma toward the original solid tumor. The semi-solid reverted form of Ehrlich ascites carcinoma is less virulent than the liquid tumor from which it originated and more virulent than the parent solid tumor. For the purposes of the examples set forth hereinafter, refer-

ence to a semi-solid Ehrlich ascites carcinoma concerns a strain propagated from a tumor caused to revert by treatment with the normal pentyl ester of indolyl-3-acetic acid.

The mechanism of action of the auxin esters in killing 5 Ehrlich carcinoma cells and in prolonging the life of infected mice is not specifically known. Because of the observed reversion of the liquid tumor to a semi-solid tumor, it is postulated that the auxin ester causes a reversion of cells to a less virulent and weaker form even 10 when no gross morphological changes are observed in the tumor. This hypothesis is strengthened by the observed reversion of transplanted semi-solid tumors to solid tumors upon treatment comprising a single one milliliter intraperitoneal injection of drug comprising 20 mg./ml. 15 normal pentyl ester of naphthyl-1-acetic acid and 50 mg./ml. glucose in the above described vehicle, or with similar treatment with the tertiary butyl ester of indolyl-3-acetic acid at a concentration of 20 mg./ml. and glucose at 50 mg./ml.

20 Analogy to the growth regulating properties of the indolyl-3-acetic acid and naphthyl-1-acetic acid in plant tissue and the growth regulating effects of related compounds forms the basis for a theory which attributes the carcinolytic activity to the location of active sites on the 25 molecule and the steric configuration of the molecule. The steric configurations of the indolyl-3-acetic acid and the esters thereof and the esters of naphthyl-1-acetic acid are sufficiently similar that if the ester is present in sufficient concentration it may react in the metabolic chain of the 30 cells to the exclusion of the indolyl-3-acetic acid thereby interrupting the metabolic chain and causing eventual death of the tumor cells.

The following examples are given to more fully illustrate the principles of this invention.

35

EXAMPLE 1

Free Ehrlich ascites tumor cells were collected from male, Webster white Swiss mice (initial body weight between 18 and 22 grams) at 6 to 10 days post transplantation, by drainage of the ascitic fluid from the abdominal cavity. One ml. of this fluid, which contained about 3×10⁸ free tumor cells per milliliter, was diluted with 10 ml. Krebs-Ringer phosphate solution, pH 6.8, containing glucose (1 mg./ml.). A 3 to 5-ml. aliquot of this intermediate mixture was diluted with an equal volume of the Krebs-Ringer phosphate-glucose solution, in which the relatively insoluble ethyl ester of indolyl-3-acetic acid (1 mg./ml.) was suspended in gum arabic (1 mg./ml.). Each ascites tumor was used as its own control, in that 40 the tumor fluid was diluted to the same final cell suspension mixture, including gum arabic, but without ethyl ester of indolyl-3-acetic acid. Incubations were carried out in glass-stoppered, dark 50-ml. Erlenmeyer flasks for a maximum of six hours at 36° C., or 20 hours at 22° C., 45 without shaking. The cell suspensions were sampled at various time intervals, and free tumor cell counts were made in triplicate immediately following appropriate dilution in Tyrode-eosin solution. Total cell counts and stained cell counts were made. The stained cells were considered 50 to represent dead cells. The Tyrode-eosin stain employed comprises 16 gm. NaCl; 400 mg. KCl; 200 mg. CaCl₂; 430 mg. MgCl₂·6H₂O; 230 mg. NaH₂PO₄·H₂O; 2 gm. glucose; 2 gm. NaHCO₃; 1 gm. Eosin yellowish; and sufficient water to make two liters.

55 The results show a lethal effect of ethyl ester of indolyl-3-acetic acid on the free ascites carcinoma cells—100-percent mortality was observed at various times, all less than five hours, depending on the sensitivity of the tumor to this agent—whereas the controls exhibited little or no death during the same period of incubation.

EXAMPLE 2

As in the above example, free ascites tumor cells were collected from male, Webster white Swiss mice (initial body weight between 18 and 22 grams) at 6 to 10 days

post transplantation by draining the ascitic fluid from the abdominal cavity. On the average, the fluid contained about 3×10^8 cells/ml. In the present example, the ascitic fluids from a number of different animals were pooled and diluted by a factor of twenty with the Krebs-Ringer phosphate solution, pH 7.15. The final mixture contained glucose at 1 mg./ml. and the substantially insoluble auxin ester at 0.5 mg./ml. suspended with gum arabic at 1 mg./ml. Controls were prepared in an identical manner, except for the omission of the auxin esters. Incubation at 37° C. and cell counting of samples withdrawn at various intervals were performed as described above.

The Krebs-Ringer-glucose solution is a medium designed only for short-term studies with isolated, live animal tissues, and the medium cannot support the life of the tumor cells indefinitely. After a four hour incubation at 37° C., some cell mortality could be observed in controls of some tumor preparation; in other preparations, little mortality was observed even after six hours. However, a 0.5 mg./ml. suspension of indolyl-3-acetic acid or of naphthyl-1-acetic acid appreciably reduced the rate of cell mortality of a sensitive tumor preparation. In contrast, the ethyl ester of indolyl-3-acetic acid killed 39% and the methyl ester of naphthyl-1-acetic acid killed 23%, of such tumor cells in two hours, compared to less than 4% death in the untreated controls. After six hours, the auxin esters had killed 100% of the cells, compared to about a 25% mortality of the controls, and only a 17% death of those cells treated with the aforementioned acids.

Similar tests were conducted with other alkyl esters of indolyl-3-acetic acid against the diluted Ehrlich ascites carcinoma in vitro. Table I illustrates the results of these tests.

TABLE II

Compound	LD ₅₀ Grams/Kilogram
Indolyl-3-acetic Acid (IAA)	0.96
Methyl ester of IAA	0.97
Ethyl ester of IAA	1.12
Propyl ester of IAA	1.10
Isopropyl ester of IAA	1.32
Normal Butyl ester of IAA	1.20
Tertiary Butyl ester of IAA	3.04
Normal Pentyl ester of IAA	1.67
Normal Hexyl ester of IAA	1.90
Normal Heptyl ester of IAA	3.17
Normal Octyl ester of IAA	2.90
Normal Nonyl ester of IAA	4.04
Normal Decyl ester of IAA	4.30

EXAMPLE 4

Life time tests were conducted on male Webster white Swiss mice (18-22 grams body weight) to determine the efficacy of the auxin ester in vivo. Tumors were transplanted into said mice by intraperitoneal injection of 0.1 ml. of ascitic fluid collected from the other similar mice known to be infected with Ehrlich ascites carcinoma. The injection contained about 3×10^6 cells of Ehrlich ascites carcinoma. Drug treatment commenced the following day and involved a single intraperitoneal injection of the auxin ester or injections of the vehicle or saline solution to serve as controls. The vehicle employed for the in vivo tests comprised 1,2 propanediol, acetylated monoglyceride (Myvacet) and a polysorbitan having an average molecular weight of about 20,000 (Tween 20) made up to the proper volume with 0.5% saline and buffered to pH 7.2-7.4 with a solution having 8 grams of tris(hydroxymethyl)

TABLE I

Indolyl-3-Acetic Acid Ester	Concentration, mg./ml.	Cell Mortality After Incubation at 37° C. (percent)			
		0 hour	1 hour	2 hours	4 hours
(Control)	0.0	2.0	2.2	2.1	2.4
Methyl	0.5	5.2	5.2	11.1	
Ethyl	0.5	6.4	41.5	91.6	
Normal Propyl	0.5	2.5	8.0	7.9	
Normal Butyl	0.5	99.7			
Tertiary Butyl	0.5	100.0			
Normal Butyl	0.5	21.7	83.9	100.0	

These tests indicate the influence of the alkyl group on the efficacy of the auxin ester in causing cell mortality. Thus it can be seen that the normal and the tertiary butyl esters of indolyl-3-acetic acid show a rate of kill four times greater than the ethyl ester. The normal pentyl ester killed tumor cells about twice as rapidly as the ethyl ester of the indolyl-3-acetic acid. The methyl and normal propyl esters were inferior to the ethyl ester in cytoidal activity, but effected a mortality rate somewhat greater than observed in the controls.

EXAMPLE 3

The toxicity of indolyl-3-acetic acid and the esters thereof was determined in a conventional manner by intraperitoneal injection of the test compound in cottonseed oil. These tests were conducted on Webster white Swiss mice. It was found that high dosages of tertiary butyl ester, normal heptyl ester, normal octyl ester, normal nonyl ester and normal decyl ester could be tolerated by the animals. Somewhat lower dosages were tolerable in the methyl ester, ethyl ester, propyl ester, isopropyl ester, normal butyl ester, normal pentyl ester and normal hexyl ester. The data for the 72 hour 50% lethal dose (LD₅₀) for certain auxin esters is presented in Table II.

aminomethane in 170 ml. of water (tris buffer). The mean survival time of a number of animals were determined for both treated and untreated control animals.

The data for this test series wherein a semi-solid Ehrlich ascites tumor was injected is set forth in Table III. The vehicle in this series comprised 18 mg./ml. 1,2 propanediol, 3 mg./ml. Myvacet, and 5 mg./ml. Tween 20 made up to volume and buffered as above. The auxin ester of indolyl-3-acetic acid was suspended in said vehicle. The mean survival time is the numerical average of the days of survival of the test animals, a plus sign (+) indicating that the test series was terminated before all of the animals had died and the balance were sacrificed.

TABLE III

70	Drug	Drug Regimen	Number of Animals	Mean Survival Time (days)
0.9% Saline	1 ml. daily for 25 days.	15	15	
Vehicle	1 ml. daily for 25 days.	10	24.8	
25 mg./ml. normal pentyl ester in vehicle.	1 ml. on first day after transplant.	10	37+	

It can be seen that the mean survival time of tumor infected animals having received a single treatment of the normal pentyl ester of indolyl-3-acetic acid is at least 2½ times the mean survival time of the controls receiving only a saline injection.

EXAMPLE 5

Another test series with a semi-solid Ehrlich ascites carcinoma was conducted in a similar manner as Example 4. The vehicle employed to suspend the auxin ester comprised 25 mg./ml. 1,2 propanediol, 5 mg./ml. Myvacet and 5 mg./ml. Tween 20 made up to volume with distilled water and buffered as above. The data from this series are set forth in Table IV.

TABLE IV

Drug	Drug Regimen	Number of Animals	Mean Survival Time (days)
0.9% Saline-----	1 ml. daily for 10 days.	20	19.4
Vehicle-----	1 ml. on first day after transplant.	17	32.3+
10 mg./ml. tertiary butyl ester, 50 mg./ml. glucose in vehicle.	1 ml. on first day after transplant.	20	40.9+

It can be seen that the treatment with the tertiary butyl ester of indolyl-3-acetic acid more than doubles the mean survival time of mice infected with a fatal carcinoma.

The data of Tables III and IV also show that an increase of mean survival time is obtained by use of the vehicle alone. A nearly identical proportionate increase in mean survival time is indicated by these data. It appears that the polysorbitan is the efficacious material causing this increase in survival and that it acts by increasing the permeability of the cell wall so that the delicate balance of cell metabolism is upset. The increase in survival time due to such a vehicle has been observed for the semi-solid Ehrlich ascites carcinoma.

EXAMPLE 6

Another test series with a semi-solid Ehrlich ascites carcinoma was conducted in a similar manner as Example 4. The vehicle employed to suspend the auxin ester comprised 25 mg./ml. 1,2 propanediol, 5 mg./ml. Myvacet and 5 mg./ml. Tween 20 made up to volume with distilled water and buffered as above. The data from this series are set forth in Table V.

TABLE V

Drug	Drug Regimen	Number of Animals	Mean Survival Time (days)
0.9% Saline-----	1 ml. on first day after transplant.	15	15
10 mg./ml. tertiary butyl ester, 50 mg./ml. glucose in vehicle.	1 ml. on first day after transplant.	20	40.9+
10 mg./ml. tertiary butyl ester, 50 mg./ml. glucose in vehicle.	1 ml. on first day after transplant +1 ml. daily of 50 mg./ml. glucose in vehicle.	30	47.3+
10 mg./ml. tertiary butyl ester, 3 mg./ml. normal undecyl ester, 50 mg./ml. glucose in vehicle.	1 ml. on first day after transplant.	30	41.2+
10 mg./ml. normal undecyl ester, 3 mg./ml. tertiary butyl ester, 50 mg./ml. glucose in vehicle.	1 ml. on first day after transplant.	30	45.5+

It can be seen from this series that all of the drug treatments increased the mean survival time of the saline treated controls. It also appears that a beneficial effect is

obtained by administering glucose solution to the test animals after auxin ester treatment. The injections of glucose made after the first day occur after the auxin ester is degraded by the tumor cells so that it appears that no direct synergism is occurring.

A test series was conducted on a group of male Webster white Swiss mice injected with a liquid Ehrlich ascites carcinoma. This tumor was transplanted by intraperitoneal injection as before. The treatment involved intraperitoneal injection of drugs as described above. The vehicle employed for the auxin ester comprised 25 mg./ml. 1,2 propanediol, 5 mg./ml. Myvacet and 5 mg./ml. Tween 20 made up to volume with 0.5% saline solution and buffered with tris buffer as above. The data from this series are set forth in Table VI.

TABLE VI

Drug	Drug Regimen	Number of Animals	Mean Survival Time (days)
0.9% Saline-----	1 ml. on first day after transplant.	30	9.3
Vehicle-----	1 ml. on first day after transplant.	30	7.2
10 mg./ml. tertiary butyl ester, 50 mg./ml. glucose in vehicle.	1 ml. on first day after transplant.	30	12.2
10 mg./ml. tertiary butyl ester, 3 mg./ml. undecyl ester, 50 mg./ml. glucose in vehicle.	1 ml. on first day after transplant.	30	10.9
10 mg./ml. tertiary butyl ester, 3 mg./ml. pentyl ester, 50 mg./ml. glucose in vehicle.	1 ml. on first day after transplant.	30	20.9

It can be seen from this series that some increase in mean survival time is obtained in animals infected with a liquid Ehrlich ascites carcinoma when treated with an auxin ester over the survival time of untreated control animals. The increases in survival time are greater than statistical variation in each instance, but not quite as great as the increases when treating the less virulent semi-solid tumor employed in Examples 4-6. The combination of tertiary butyl ester with the normal pentyl ester of indolyl-3-acetic acid doubles the lifetime of the animals and demonstrates a synergism between these compounds.

EXAMPLE 8

A series of tests were performed with male Webster white Swiss mice in the terminal stages of the Ehrlich ascites carcinoma. The mice employed in these tests were implanted with the subject tumor as previously described seven days previous to the tests. Drugs were injected intraperitoneally in the mice as one milliliter of solution seven days after transplant. The solution comprised the auxin ester in a vehicle containing 18 mg./ml. 1,2 propanediol; 3 mg./ml. Myvacet; 5 mg./ml. Tween 20, diluted and buffered to pH of 7.2 to 7.4 with tris buffer as recited above. One hour after injection of the test solution the animals were sacrificed and the ascitic fluid drained. A cell count was made after staining the cells with Tyrodeosin solution. Total free cell counts and stained free cell counts were made. The stained cells were considered to represent dead cells. Control tests were made employing injections of glucose and injections of glutathione in the vehicle. A small percentage of dead cells was noted in both of the controls. Additionally doses of the normal pentyl and normal heptyl esters of indolyl-3-acetic acid were made either alone in the vehicle or in combination with glucose and glutathione in the vehicle. The data obtained from this series of acute tests are set forth in Table VII.

TABLE VII

Drug	Total cells	Dead Cells	Percent Kill	Number Animals
Glucose, 50 mg./ml.	15	3	11	4
	12	1		
	14	2		
	23	3		
	34	3		
	32	2		
	49	4		
Glutathione, 20 mg./ml.	49	5	9	4
	46	4		
	45	3		
	40	4		
	50	5		
	6	5		
Normal pentyl ester, 25 mg./ml.	5	3	80	4
	4	3		
	7	7		
	26	26		
	23	21		
	3	3		
	2	2		
Normal heptyl ester, 25 mg./ml.	15	15	97	5
	12	12		
	40	40		
	50	50		
	12	11		
	13	13		
	86	81		
Glucose, 50 mg./ml.	80	78	96	4

It can be seen from these series of tests that a substantial rate of kill of tumor cells in the ascitic fluid is obtained by treatment with the normal pentyl and normal heptyl esters of indolyl-3-acetic acid.

EXAMPLE 9

A group of 50 male Webster white Swiss mice were injected with a liquid Ehrlich ascites carcinoma as described above. On the first day after transplanting the tumor, each animal received a one milliliter drug treatment. One half of the animals received 0.9% saline, and the other half received a suspension comprising 10 mg./ml. normal propyl ester of naphthyl-1-acetic acid, 50 mg./ml. glucose, 25 mg./ml. 1,2 propanediol, 5 mg./ml. Myvacet, and 5 mg./ml. Tween 20 made up to volume with 0.5% saline solution and buffered with tris buffer as above. The saline treated animals showed a mean survival time of 9.5 days, whereas those treated with the auxin ester showed a mean survival time of 24.3 days, an increase of about 2½ times.

Another group of 50 male Webster white Swiss mice received transplants of a semi-solid Ehrlich ascites carcinoma as described above. One-half of this group received a saline treatment as above, and the other half received treatment with the same suspension of normal propyl ester of naphthyl-1-acetic acid as above. The saline treated animals showed a mean survival time of 14.3 days, demonstrating that somewhat lower virulence of the semi-solid reversion than the liquid tumor. The auxin ester treated animals showed a mean survival time of 21.6 days indicating a significant increase in survival.

EXAMPLE 10

A group of 40 male Webster white Swiss mice received transplants of a semi-solid Ehrlich ascites carcinoma by intraperitoneal injection. On the first day after transplant one half of the animals received one milliliter of 0.9% saline solution. On the same day the other half of the animals received one milliliter of suspension comprising 20 mg./ml. normal pentyl ester of naphthyl-1-acetic acid, 50 mg./ml. glucose, 25 mg./ml. 1,2 propanediol, 5 mg./ml. Myvacet, and 5 mg./ml. Tween 20 made up to volume with 0.5% saline solution and buffered with tris buffer as described above. The saline treated animals showed a mean survival time of 15.0 days, whereas the auxin ester treated animals showed a mean survival time of 56.1 days, an improvement substantially over 3½ times. Additionally the animals treated with the auxin ester no longer exhibited the semi-solid tumor transplanted, but rather were subject to a reverted hard tumor located in the peritoneal cav-

ity or elsewhere. Thus it is clear that the normal pentyl ester of naphthyl-1-acetic acid caused a reversion of the Ehrlich ascites carcinoma to a solid form.

It is to be understood that the above described examples are merely illustrative of the application of the principles of this invention. Those skilled in the art may readily devise other variations that will embody the principles of this invention. It is therefore to be understood that within the scope of the appended claims the invention may be practiced otherwise than as specifically described.

What is claimed is:

1. A method for treatment of Ehrlich ascites carcinoma in mice comprising administering intraperitoneally in a mouse suffering with Ehrlich ascites carcinoma an aqueous pharmaceutical carrier containing glucose and from 2 to 50 milligrams of alkyl ester of an auxin per milliliter of carrier wherein said alkyl ester of an auxin is selected from the class consisting of ethyl ester of indolyl-3-acetic acid, normal butyl ester of indolyl-3-acetic acid, tertiary butyl ester of indolyl-3-acetic acid, normal pentyl ester of indolyl-3-acetic acid, normal heptyl ester of indolyl-3-acetic acid, and normal undecyl ester of indolyl-3-acetic acid.
2. A method of killing Ehrlich ascites carcinoma tumor cells in mice comprising administering intraperitoneally an aqueous pharmaceutical carrier containing glucose and from 200 to 600 milligrams of auxin ester per kilogram of body weight wherein said auxin ester is selected from the class consisting of ethyl ester of indolyl-3-acetic acid, normal butyl ester of indolyl-3-acetic acid, tertiary butyl ester of indolyl-3-acetic acid, normal pentyl ester of indolyl-3-acetic acid, normal heptyl ester of indolyl-3-acetic acid, and normal undecyl ester of indolyl-3-acetic acid.

3. A method of killing Ehrlich ascites carcinoma cells in mice comprising intraperitoneally injecting a mouse with an aqueous pharmaceutical carrier containing an effective amount of an alkyl ester of an auxin for killing Ehrlich ascites carcinoma cells wherein said alkyl ester of an auxin is selected from the class consisting of ethyl ester of indolyl-3-acetic acid, normal butyl ester of indolyl-3-acetic acid, tertiary butyl ester of indolyl-3-acetic acid, normal pentyl ester of indolyl-3-acetic acid, normal heptyl ester of indolyl-3-acetic acid, and normal undecyl ester of indolyl-3-acetic acid.
4. A method of killing Ehrlich ascites carcinoma cells in mice comprising intraperitoneally injecting a mouse with an aqueous pharmaceutical carrier containing glucose and an effective amount of an alkyl ester of indolyl-3-acetic acid for killing Ehrlich ascites carcinoma cells wherein the alkyl group is selected from the class consist-

ing of ethyl, normal butyl, tertiary butyl, normal pentyl, normal heptyl, and normal undecyl.

5. A method of killing Ehrlich ascites carcinoma cells comprising intraperitoneally injecting a mouse with an aqueous pharmaceutical carrier containing glucose and an effective amount of the ethyl ester of indolyl-3-acetic acid for killing Ehrlich ascites carcinoma cells.

6. A method of killing Ehrlich ascites carcinoma cells comprising intraperitoneally injecting a mouse with an aqueous pharmaceutical carrier containing glucose and an effective amount of the normal butyl ester of indolyl-3-acetic acid for killing Ehrlich ascites carcinoma cells.

7. A method of killing Ehrlich ascites carcinoma cells comprising intraperitoneally injecting a mouse with an aqueous pharmaceutical carrier containing glucose and an effective amount of the tertiary butyl ester of indolyl-3-acetic acid for killing Ehrlich ascites carcinoma cells.

8. A method of killing Ehrlich ascites carcinoma cells comprising intraperitoneally injecting a mouse with an aqueous pharmaceutical carrier containing glucose and an effective amount of the normal pentyl ester of indolyl-3-acetic acid for killing Ehrlich ascites carcinoma cells.

9. A method of killing Ehrlich ascites carcinoma cells comprising intraperitoneally injecting a mouse with an aqueous pharmaceutical carrier containing glucose and an effective amount of the normal heptyl ester of indolyl-3-acetic acid for killing Ehrlich ascites carcinoma cells.

10. A method of killing Ehrlich ascites carcinoma cells comprising intraperitoneally injecting a mouse with an aqueous pharmaceutical carrier containing glucose and an effective amount of the normal undecyl ester of indolyl-3-acetic acid for killing Ehrlich ascites carcinoma cells.

11. A chemotherapeutic composition comprising an aqueous solution of glucose having therein a suspension of the normal butyl ester of indolyl-3-acetic acid in a concentration of from 2 to 50 milligrams per milliliter of solution.

12. A chemotherapeutic composition comprising an aqueous solution of glucose having therein a suspension of the tertiary butyl ester of indolyl-3-acetic acid in a concentration of from 2 to 50 milligrams per milliliter of solution.

13. A chemotherapeutic composition comprising an aqueous solution of glucose having therein a suspension of the normal pentyl ester of indolyl-3-acetic acid in a concentration of from 2 to 50 milligrams per milliliter of solution.

14. A chemotherapeutic composition comprising an aqueous solution of glucose having therein a suspension

of the normal heptyl ester of indolyl-3-acetic acid in a concentration of from 2 to 50 milligrams per milliliter of solution.

15. A chemotherapeutic composition comprising an aqueous solution of glucose having therein a suspension of the normal undecyl ester of indolyl-3-acetic acid in a concentration of from 2 to 50 milligrams per milliliter of solution.

16. A chemotherapeutic composition comprising an aqueous solution of glucose having therein a suspension of the tertiary butyl ester of indolyl-3-acetic acid and the normal pentyl ester of indolyl-3-acetic acid with total concentration of said esters of from 2 to 50 milligrams per milliliter of solution.

17. A chemotherapeutic suspension comprising: a poly-sorbitan surface active agent; acetylated monoglyceride; water; 1,2-propanediol; glucose and an effective amount for chemotherapy of an alkyl ester of indolyl-3-acetic acid wherein the alkyl group is selected from the class consisting of ethyl, normal butyl, tertiary butyl, normal pentyl, normal heptyl and normal undecyl.
